CLAIM

(21) Appl. No.: **29/514,548**

The ornamental design for an adjustable display holder for a handheld device, as shown and described.

(22) Filed: **Jan. 14, 2015**

DESCRIPTION

(51) **LOC (10) Cl.** **14-03**

FIG. 1 is a back view of the claimed adjustable display holder for a handheld device in an orientation for holding a display device in a vertical orientation;

(52) **U.S. Cl.**

FIG. 2 is a bottom view thereof;

USPC **D14/253**

FIG. 3 is a front view thereof;

(58) **Field of Classification Search**

FIG. 4 is an isometric front view thereof;

USPC D14/253, 432, 434, 440, 447, 439,

FIG. 5 is a left view thereof;

D14/451, 452, 457, 250, 251; D12/415,

FIG. 6 is a right view thereof;

D12/114, 420, 417, 223; D6/406.3, 406.4,

FIG. 7 is a top view thereof;

D6/406.5, 406.6, 310, 407; D3/218;

FIG. 8 is a top view of the claimed adjustable display holder for a handheld device in an orientation for holding a display device in a horizontal orientation;

D8/349

FIG. 9 is an isometric front view thereof;

CPC H04M 1/04; H04M 1/06; H04M 1/11;

FIG. 10 is an isometric view thereof holding a adjustable

H04M 1/12; F16M 13/00; B60R 11/00;

display holder for a handheld device; and,

B60R 11/02; H05K 7/00

FIG. 11 is an isometric view of the adjustable display holder for a handheld device in the orientation of FIG. 4 holding a display device.

See application file for complete search history.

The dash-dash broken lines in the drawings depict parts of the adjustable display holder for a handheld device that form no part of the claimed design. The dot-dot broken lines in the drawings depict a hand held device for display that forms no part of the claimed design.
